(57) **CLAIM**

The ornamental design for a firearm chassis, as shown and described.

DESCRIPTION

FIG. 1 is a right elevation view of the claimed firearm chassis.

FIG. 2 is a left elevation view of the firearm chassis of FIG. 1.

FIG. 3 is a top plan view of the firearm chassis of FIG. 1.

FIG. 4 is a bottom plan view of the firearm chassis of FIG. 1.
FIG. 5 is a front elevation view of the firearm chassis of FIG.

1.
FIG. 6 is a rear elevation view of the firearm chassis of FIG.
1.

FIG. 7 is a bottom rear perspective view of the firearm chassis of FIG. 1.

FIG. 8 is a top front perspective view of the firearm chassis of FIG. 1.

FIG. 9 is a top rear perspective view of the firearm chassis of FIG. 1.

FIG. 10 is a bottom front perspective view of the firearm chassis of FIG. 1.

FIG. 11 is a bottom rear perspective view of the firearm chassis of FIG. 1.

FIG. 12 is a top front perspective view of the firearm chassis of FIG. 1.

FIG. 13 is a top rear perspective view of the firearm chassis of FIG. 1.

FIG. 14 is a bottom front perspective view of the firearm chassis of FIG. 1.

FIG. 15 is a right elevation view of the firearm chassis of FIG.
1, folded.

FIG. 16 is a left elevation view of the firearm chassis of FIG.
15.

FIG. 17 is a top plan view of the firearm chassis of FIG. 15.

FIG. 18 is a bottom plan view of the firearm chassis of FIG.
15.

FIG. 19 is a front elevation view of the firearm chassis of FIG.
15.

FIG. 20 is a rear elevation view of the firearm chassis of FIG.
15.

FIG. 21 is a top front (left) perspective view of the firearm chassis of FIG. 15.

FIG. 22 is a top rear perspective view of the firearm chassis of FIG. 15.

FIG. 23 is a bottom front perspective view of the firearm chassis of FIG. 15; and,

FIG. 24 is a top front perspective view of the firearm chassis of FIG. 15.

The broken lines in FIGS. 2, 11-15, and 22-24 depict a logo and are illustrative of environment and not intended to form a part of the claimed design.
